UNITED STATES PATENT OFFICE.

ALBERT OPPENHEIM, OF NEW YORK, N. Y.

CLASP-STUD.

1,369,463.

Specification of Letters Patent. Patented Feb. 22, 1921.

Application filed October 4, 1920. Serial No. 414,470.

To all whom it may concern:

Be it known that I, ALBERT OPPENHEIM, a citizen of the United States, residing at 600 W. 118th St., New York, county of New York, State of New York, have invented an Improvement in Clasp-Studs, of which the following is a specification.

This invention relates to clasp studs such as are used in garment supporters, and the like, and has for its object to provide a stud consisting of head, shank and base, which shall be formed mechanically from a blank of wire.

With this end in view I have devised the novel wire stud which I will now describe referring to the accompanying drawing, forming a part of this specification, and using reference characters to indicate the several parts.

Figure 1 is a view in elevation illustrating the use of my novel stud in a garter;

Fig. 2, a section on a greater enlarged scale, on the line 2—2 in Fig. 1;

Fig. 3, a perspective view of the rubber collet, which incloses the head and shank; and

Fig. 4 is a perspective view of the stud detached.

10 denotes the band of a garter which 30 may be of any ordinary material or design, and 13 the ordinary metallic, clasping loop, which in use, engages the stud as clearly shown. The clasping loop is attached to the band in any ordinary or preferred manner 35 as by means of a loop 12 of textile web, and the stud is carried by a longer loop 14 of textile web which is also attached to the band.

The stud, which is denoted as a whole by 40 15, comprises a head 26, a shank 21, and a base 20. The head, which lies approximately parallel to the plane of the base, is formed from the mid-length of the wire blank, said blank being curved to form an approximately circular head of the required size. Just under the head the halves of the blank are bent inward and then downward close together to form one half of the shank, it being noted that the head overhangs the 50 shank. At the lower end of the shank the halves of the blank are bent outward, from each other, at approximately a right angle and are then curved and recurved to form ends respectively of the web slots 16 and 17.

The other ends of said slots are formed by 55 curving and recurring the halves of the blank again, the ends of the blank being then turned upward and lying in contact with each other and in contact with the other two strands of wire in the shank, the ends terminating under the head. It will thus be seen that the shank is comprised of four strands of wire, lying in contact, said strands being indicated by 22, 23, 24 and 25.

The stud is completed by placing thereon 65 a yielding collet which is molded from rubber. The upper end of the collet is enlarged, as at 28, and is provided with a recess 29 which receives the head of the stud, the recess being preferably large enough to receive 70 the head so that the latter will lie wholly below the upper end of the collet.

The stud is attached to web loop 14 by passing one end of the loop downward through slot 16 then across and upward 75 through slot 17 then around backward and under the stud, the ends of the loop being stitched or otherwise secured to the garter band.

Having thus described my invention, I 80 claim:

1. A clasp stud formed from a wire blank and comprising an approximately circular head formed from the mid-length of the blank, the halves of the blank being then 85 bent inward and downward to form half of a shank, the halves being then bent away from each other and curved and recurved twice to form web slots, and then upward to complete the shank.

2. A clasp stud formed from a wire blank and comprising a head formed from the mid-length of the blank, the halves of the blank being then bent downward to form half of the shank, the halves being then curved 95 and recurved to form web slots, and then bent upward to complete the shank.

3. A clasp stud formed from a wire blank and comprising a head formed from the mid-length of the blank, the halves of the blank being then bent downward to form half of the shank, the halves being then 100 curved and recurved to form web slots, and then bent upward, and terminating under the head.

In testimony whereof I affix my signature.

ALBERT OPPENHEIM.
